UNITED STATES PATENT OFFICE.

ALBERT MALSIN, OF NEW YORK, N. Y.

LADY'S DRESS.

1,119,297.

Specification of Letters Patent.

Patented Dec. 1, 1914.

Application filed September 15, 1913. Serial No. 789,733.

To all whom it may concern:

Be it known that I, ALBERT MALSIN, citizen of the United States of America, residing at New York, in the county of New 5 York and State of New York, have invented certain new and useful Improvements in Ladies' Dresses, of which the following is a specification.

The present invention has for its object 10 to provide a combination waist and skirt, both adjustable in width, and particularly adapted for use during pregnancy.

This invention particularly relates to 15 dresses of such texture, that the gathering or plaiting of the excess width or fullness would be impracticable and render the dress very clumsy.

To accomplish my object, I provide a 20 waist, the waist line of which by means of 20 elastics is rendered adjustable in width, and a skirt, which is slit either partially or throughout its entire length either at the side or in front, and which only at the rear at the waist line is permanently fixed to the 25 waist, while at the sides and in front it is detached from the waist. The width of the skirt is made much larger than the width of a normal person, so that when the skirt is worn in normal condition the excess parts 30 thereof at the slit will overlap one another more, and in abnormal condition less to fit the body. The two overlapping parts may be affixed to one another by any suitable means as hooks and eyes, of which there 35 may be a great plurality arranged in rows, so that the overlapping parts may be fixed to each other according to adjustment.

The novel feature of the dress resides in 40 that the skirt is only partly permanently fixed to the waist and the unattached part thereof is longitudinally slit, whereby the adjustability of the skirt in width is rendered possible, without requiring any alteration or change of the shape of the skirt. 45 Owing to the new construction, the skirt will always fit the wearer whether in normal or abnormal condition, and have a neat appearance.

To render my invention more clear, the 50 same is illustrated in the accompanying drawing in which similar reference characters denote corresponding parts and in which—

Figure 1 shows the dress in normal condition; Fig. 2 in abnormal condition and 55

Fig. 3 shows an elevation of the dress, only a part of the waist and the skirt being shown.

The combination dress consists of the waist *a* and the skirt *b*. The waist is made 60 adjustable in width by an elastic band *c* provided at the waist line, or in any other suitable manner. The skirt part *b* of the dress is permanently fixed to the waist only at the rear part of the waist line, while the 65 rest is detached from the waist, as at *b'*, *b'*. This detached part of the skirt is slit either partially or throughout the entire length of the skirt from the waist line on, as at 70 *d*, *d*. The width of the skirt is so measured 75 as to be larger than the width of a normal person, so that when applied by the latter the excess portions of the skirt's width will fold over or overlap one another, as indicated by the dotted line *x* in Fig. 1, to the extent required for the proper fit. With a 80 larger width, the excess portions will overlap a smaller extent, as indicated by the dotted line *y* in Fig. 2.

The appearance or shape of the skirt in all 80 instances remains the same.

The overlapping parts may be secured to one another by hooks and eyes, *e*, *f* or the like, of which there may be a great number arranged in rows in close proximity to one another, so as to enable the closing of the skirt at different widths.

What I claim and desire to secure by Letters Patent is:

1. A lady's dress, consisting of a waist 90 and a skirt, both adjustable in width, the skirt being only partially permanently fixed to the waist and the unattached portion thereof being slit longitudinally from the waist line, and means for affixing the adjacent slit parts to one another.

2. A lady's dress, consisting of a waist and a skirt, both adjustable in width, the skirt being only at the rear permanently fixed to the waist and the unattached portion 100 thereof being slit longitudinally from the waist line, and means for affixing the adjustable slit parts to one another.

3. In a lady's dress, the combination with a waist having an elastic waist band, of a 105 skirt which is only partially permanently fixed to said waist and which is slit longitudinally from the waist line, including means for affixing the slit parts to one another.

4. In a lady's dress, the combination with
a waist having an elastic waist band, of a
skirt which is only at the rear permanently
fixed to the waist and which is slit longi-
5. tudinally from the waist line, including
means for affixing the slit parts to one an-
other.

In testimony whereof I affix my signature
in presence of witnesses.

ALBERT MALSIN.
